(57) **CLAIM**

The ornamental design for a closure, as shown and described.

DESCRIPTION

FIG. 1 is a front isometric view of a closure showing our new design with the closure in the closed condition, and a user's finger can push down on an area on the rear region of the top of an element of the closure to pivot the element;

FIG. 2 is a rear isometric view thereof;

FIG. 3 is a top view thereof;

FIG. 4 is a front elevational view thereof;

FIG. 5 is a rear elevational view thereof; and,

FIG. 6 is a right side elevational view thereof, the left side elevational view thereof being a mirror image.
